Attorney.

UNITED STATES PATENT OFFICE.

CHARLES G. HUTCHINSON, OF CHICAGO, ILLINOIS.

BOTTLING-MACHINE.

SPECIFICATION forming part of Letters Patent No. 225,475, dated March 16, 1880.

Application filed January 13, 1880.

To all whom it may concern:

Be it known that I, CHARLES G. HUTCHINSON, of Chicago, in the county of Cook and State of Illinois, have invented certain new and useful Improvements in Bottling-Machines, of which the following, in connection with the accompanying drawings, is a specification.

In the drawings, Figure 1 is an end elevation of a bottling-machine embodying my invention; Fig. 2, a vertical central section from side to side, or from front to rear, of the machine; and Fig. 3 is a section in the plane of the line *x x* of Fig. 2.

Like letters of reference indicate like parts. My invention has for its object the providing of mechanical means for filling and closing with facility bottles having internal stoppers provided with upwardly-projecting stems for suspending the stoppers properly with relation to the necks, and which stems have a loop or eye at their upper ends to facilitate the closing or tightening of the stopper.

To this end, my invention consists of the means, substantially as hereinafter set forth, which I employ for the purpose above mentioned.

In the drawings, A represents a bottle, and B is a stopper, of the class hereinbefore referred to. C is a stand, table, or bench. D is a rod or bar passing up freely through the bench C. E is a disk or bottle-support on the upper end of the rod D. F is a treadle or lever pivoted to the lower part of the bench or having other suitable bearing.

The lower end of the rod D is pivoted or otherwise jointed to the treadle F in such manner that the vibration of the latter will move the support E up and down alternately.

G is a bracket or support applied to the bench C or to some suitable fixture. H is a hollow cylinder supported by the bracket G in such manner that the lower or open end of the cylinder shall be directly over the disk E. I is an annular cushion in the lower end of the cylinder H, and J is an induction-tube entering the cylinder. This induction-tube should be provided with a cock, for the purpose hereinafter mentioned; but as this cock is intended to perform the ordinary and well-known function of such devices, I have not here shown one.

K is a stuffing-box, in which the upper end of the cylinder H terminates. L is a lever pivoted at one end to an arm extending from the bracket G. M is a plunger pivoted to the lever L, and passing down through the stuffing-box and through the cylinder, and made hook-shaped at its lower end, as shown at *a*.

The length of the plunger M is such that it may extend sufficiently below the cylinder H to be hooked into the upper end of the stem of the stopper B when the bottle and stopper are arranged in the positions indicated by the dotted or broken lines shown in Fig. 1—viz., when the bottle and stopper are in their lowest est positions.

To use the filler and closer now described I proceed as follows: The bottle to be filled is placed on the disk or bottle-support E, the stopper being first depressed or pushed down to its open position, where it will be suspended approximately in a central position with relation to the neck of the bottle. The hook *a* is then inserted into the loop of the stem of the stopper, as indicated in Figs. 1 and 3; or the stem may be hooked upon the hook *a* by being inserted into the lower end of the cylinder and moved until the proper connection with the hook is made. Usually the act of placing the bottle on its support and of hooking the stopper-stem to the plunger may be performed at about the same time. I then depress the treadle, by which means the bottle will be held up firmly against the cushion I. The liquor may now be allowed to enter through the pipe J, and as soon as the bottle is filled the lever L should be raised, enough to draw the stopper to its closed position.

While raising the bottle-support the lever L may also be raised to an equal extent without closing the stopper; but it is not necessary that this should be done, for the hook will find its connection with the stopper-stem if the hand-lever be raised after the bottle is forced up against the cushion I, provided the connection is first made in the manner already described, or the parts arranged for connection on the drawing up of the hook *a*. The raising of the hook *a* in the manner described closes the bottle, and after it is closed the treadle and the hand-lever should be released, when the bottle will descend to a position which will

admit of its being easily removed; but before releasing the bottle the flow through the pipe J should be shut off, it being understood that the cock therein was opened after the bottle 5 was raised to its cushion.

The most common use to which this machine will be applied, probably, will be the bottling of aerated liquors, and when so used the cylinder H should be provided with an air-vent 10 to prevent the gas from interfering with the filling of the bottle; but as such a vent is not absolutely essential, even when the liquors are effervescent, though a vent is then preferable, and as no vent is required for non-effervescent 15 liquors, I have not here shown and described such a vent; and the construction, application, and operation of such a vent, for the purposes set forth, is, moreover, well known to those familiar with the art to which my invention re- 20 lates.

It may also be here stated that the filler and closer now described may be used in connection with a sirup-gage in any well-known or suitable way when aerated liquors are to be 25 bottled.

It is obvious, from the foregoing description, that the cylinder H may be moved downward

upon the bottle instead of moving the bottle upward to the cylinder, and that in the former case the bottle may be supported directly upon a fixed table or support, and I would therefore regard a movable cylinder, instead of the fixed cylinder herein shown, a mere modification of construction within the scope of the essential principles of my invention. 30

I am aware that a plunger provided on its lower end with claws or fingers for seizing the sides of the plugs or valves has heretofore been made; and I do not therefore here intend to claim such; but, 35

Having thus described my invention, what I claim as new, and desire to secure by Letters Patent, is—

The combination, in a bottling-machine, of the plunger M, having on its lower end the hook a, for entering a loop or eye in the stem of a bottle-stopper, the stuffing-box K, and the cylinder H, substantially as and for the purposes specified. 40

CHARLES G. HUTCHINSON.
